DESIGN FOR A GILET

Edward Baruch, New York, N. Y.

Application March 2, 1937, Serial No. 67,943

Term of patent 3½ years

To all whom it may concern:

Be it known that I, Edward Baruch, a citizen of the United States of America, residing in Manhattan, county of New York and State of New York, have invented a new, original, and ornamental Design for a Gilet, of which the following is a specification, reference being had to the accompanying drawing, forming part thereof, wherein,

The figure is a plan view of a gilet showing my new design.

The characteristic feature of my design resides in the combination on a gilet of the instant configuration having a partially stitched down diagonal tuck descending from each side of the neckline in association with the fagoting and bows as shown.

I claim:

The ornamental design for a gilet, substantially as shown and described.

EDWARD BARUCH.
